US00D835661S

(12) **United States Design Patent** (10) **Patent No.:** **US D835,661 S**
Chaudhri et al. (45) **Date of Patent:** **** Dec. 11, 2018**

(54) **DISPLAY SCREEN OR PORTION THEREOF WITH GRAPHICAL USER INTERFACE**(71) Applicant: **Apple Inc.**, Cupertino, CA (US)(72) Inventors: **Imran Chaudhri**, San Francisco, CA (US); **Elizabeth Caroline Cranfill**, San Francisco, CA (US); **Tiffany Jon**, Sunnyvale, CA (US); **Christopher Daryl Soli**, Mountain View, CA (US)(73) Assignee: **Apple Inc.**, Cupertino, CA (US)(***) Term: **15 Years**(21) Appl. No.: **29/584,397**(22) Filed: **Nov. 14, 2016****Related U.S. Application Data**

(63) Continuation of application No. 29/503,909, filed on Sep. 30, 2014, now Pat. No. Des. 771,646.

(51) **LOC (11) Cl.** ..... **14-04**(52) **U.S. Cl.**USPC ..... **D14/487**(58) **Field of Classification Search**USPC **D14/485-495**

Primary Examiner — Shannon W Morgan(74) *Attorney, Agent, or Firm* — Sterne, Kessler, Goldstein & Fox P.L.L.C.(57) **CLAIM**

The ornamental design for a display screen or portion thereof with graphical user interface, as shown and described.

DESCRIPTION

The FIGURE is a front view of a display screen or portion thereof with graphical user interface showing the claimed design.

The broken lines in the FIGURE show a display screen or portion thereof, and form no part of the claimed design.
